[57] CLAIM

The ornamental design for tee shirt tote bag, as shown and described.

DESCRIPTION

FIG. 1 is a perspective view of a tee shirt tote bag showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

The dominant feature of the invention resides in the design of a tee shirt tote bag, namely a tank top tee shirt formed in the shape of a tote bag by stitching together the bottom of the said tee shirt. The broken lines showing of a design, the Boston Tee Bag Co., Cape Cod are for illustrative purposes only and form no part of the claimed design.
